United States Patent Office

Des. 231,449
Patented Apr. 23, 1974

231,449

PROJECTILE NOSE

David D. Abbott, Baltimore County, Md., assignor to
AAI Corporation, Cockeysville, Md.

Filed Sept. 24, 1971, Ser. No. 183,736

Term of patent 14 years

Int. Cl. D22—03

U.S. Cl. D22—10

FIG. 1

FIG. 2

FIG. 3

FIG. 4

FIG. 1 is a view in perspective of a projectile nose according to the invention, the view being taken as viewed toward the front end of the nose.

FIG. 2 is a side elevation view of the projectile nose of FIG. 1.

FIG. 3 is a front end view of the projectile nose of FIG. 1.

FIG. 4 is a rear view of the projectile nose of FIG. 1.

I claim:

The ornamental design for a projectile nose, substantially as shown.
